INVENTOR

Benjamin E. Getchell,

BY

UNITED STATES PATENT OFFICE.

BENJAMIN E. GETCHELL, OF PLAINVILLE, CONNECTICUT, ASSIGNOR TO THE TRUM-BULL ELECTRIC MANUFACTURING COMPANY, OF PLAINVILLE, CONNECTICUT, A CORPORATION OF CONNECTICUT.

ELECTRIC SWITCH.

Application filed April 13, 1926. Serial No. 101,688.

My invention relates particularly to so-called safety or enclosed switches.

One object is to provide a construction of this character which can be operated when the box is closed but which requires that the switch must be opened before the box can be opened.

Another object is to provide a construction in which, when the switch is open, the switch blades, contacts and load side terminals are entirely disconnected from the circuit or what is known as "dead".

Another object is to provide a construction of this character which can be made up largely out of standard parts, such as are commonly used in switch constructions.

Another object is to provide a closed switch having a fuse receptacle which is entirely disconnected from the circuit when the switch is open, regardless of which switch terminals the line wires may be connected with.

I have shown the invention as applied to one type of switch and one type of box as typical of others to which the invention may be applied. The unit switch consists of two hinged blades which are linked together so as to be simultaneously operated. The fuse unit is connected between the hinged ends of these blades so that when the switch is open, both fuse terminals are dead. Other details of the improvement will be understood from the following specification.

Fig. 1 is a perspective view of a construction embodying my invention in the form of a safety switch, the box being closed and the switch in the closed circuit position.

Fig. 2 is a perspective view showing various elements of a switch and fuse unit separated.

Fig. 3 is a front view of the construction shown in Fig. 1 with the switch in the off position and the fuse sockets exposed.

Fig. 4 is an end view of the switch and fuse units without the box.

Fig. 5 is a front view and partial section showing a single switch unit in the closed circuit position.

Fig. 6 is a full-sized transverse section of the construction showing a single switch and fuse unit in its box with the parts of the switch in the closed circuit position.

Fig. 7 is a fragmentary side view and section showing one of the switch blades and connected parts.

Fig. 8 is a similar view showing the other switch blade and connected parts in full lines, and showing in dot-and-dash lines both blades in the open circuit position.

Fig. 9 is a longitudinal sectional view showing a modification of the switch proper without fuses.

Fig. 10 is a plan view of the same omitting the switch blades.

Fig. 11 is a plan view of the connector of the form employed in the structure of Figs. 9 and 10.

The box 10 may be of any suitable character provided with the usual knock-outs or means for admitting conduits or cables. It is provided with a cover 11, preferably hinged and normally held by a suitable catch 12.

The conducting parts are all carried by an insulating base 13 suitably secured in the box, for instance, by screws 14.

The circuit terminals 15 and 16 of one unit of the switch are shown in Fig. 8 and are of any suitable character. The spring jaws 17 and 18 are of any suitable character secured to the base in any suitable way, as, for instance, by usual screws 19 and 20, respectively. The switch blades 21 and 22, of any suitable character, are hinged in the usual way to suitable posts or jaws 23 and 24, and secured to the base in any suitable manner, as, for instance, by the screws 25 and 26, respectively. Any suitable type of fuse and fuse socket may be employed. I have shown the fuse terminals for a screw plug 33, these terminals being the center screw 27 and the screw shell 28, of standard type. The fuse terminals are connected, respectively, to the supports 23 and 24 by members 29 and 30. The center screw 27 screws into the outer end of the arm 29, and the forked end of the arm 30 rests on the bottom of the screw shell 28 in the usual manner of fuse socket connections. The fuse terminals are preferably mounted in an insulating block 31, which has a rim or shoulder 32 which projects through an opening in the cover 11. When the switch is closed, the circuit through the unit just described extends consecutively through the following elements—terminal 15, jaws 17, blade 21, post

23, arm 29, center screw 27, fuse plug 33, screw shell 28, arm 30, post 24, switch blade 22, jaw 18 and switch terminal 16.

The two switch blades 21 and 22 are connected by a folding or hinged link 34 which is guided in a recess 35 in the base 13. The switch is operated by a crank 36 pivoted in the opposite walls of the box and which has a loose connection in the slot of the insulating member 37 which is secured to one of the switch blades. This crank 36 has an external operating member or handle 38. Fig. 1 shows the handle in the closed circuit position. To open the switch the handle is pulled downward which rocks the crank 36 and thus swings the switch blade 22 to the open circuit dot-and-dash position of Fig. 8. The link 34 which connects the blade 22 to the blade 21 operates the blade 21 simultaneously with blade 22 so that the circuit is broken at two places simultaneously. When the switch handle is moved upwardly, the switch is closed, the link 34 being guided in the recess 35 in the base. The crank 36 is pivoted at a point remote from the pivot centers of the blades 21 and 22 so that, although the handle has the desired 90° throw, the switch blades have only approximately a 30° throw. The parts are so constructed and connected that the blades move in unison so as to insure simultaneous making and breaking of the circuit at the proper times at two points.

I have shown the invention as applied to a form of switch having a special interlocking mechanism with the cover. This protective mechanism consists of a housing 39 secured to the cover having an opening or passage 40 which is normally closed by a slide 41 so that the fuses are entirely enclosed. This slide 41 has a flange 42 which extends alongside of the operating handle 28 so that when the switch is closed, the slide cannot be opened. Consequently the fuses are inaccessible while the switch is closed. This slide also has a hook 43 which embraces the switch handle so that the cover 11 of the box cannot be opened when the switch is closed. The box may also be provided with a guard 44 around a part of the handle which may be sealed or locked to the handle in any suitable manner. The slide 41, when open, also serves to prevent the closing of the switch.

In the form of construction shown in Figs. 9 and 10 the switch blades 50 and 51 are hinged respectively to the posts or jaws 52 and 53 which are secured to the base by the screws 54 and 55 respectively. The two posts 52 and 53 are electrically connected in a suitable manner as for instance by means of a plate or bar 56. The two blades are mechanically connected by a hinged link 57 so that the blades are compelled to operate together. The base is preferably provided

with a slot or passage 58 for guiding the link 57. The connector 56 in the form shown is designed to extend around from the screw 54 to the screw 55 clear of the guide passage 58. 70

The jaws 59 and 60 are of the usual type secured to the base in any suitable manner and provided with circuit terminals 61 and 62 respectively.

It will be seen from this that the construction is adapted to make and break the circuit at two points and when the circuit is open both switch blades and connected parts are entirely dead. 75

I claim:

1. An electric switch comprising an insulating switch base, posts carried thereby, blades hinged to said posts, a folding link connecting said blades, an insulating fuse carrying member supported from said posts 85 and having fuse terminals electrically connected to said blades at all times, and means for operating said blades simultaneously.

2. An electric switch comprising an insulating switch base, posts carried thereby, 90 blades hinged to said posts, a link connecting said blades, means for guiding said link in said base, an insulating fuse carrying member, arms supported from said posts, fuse terminals in said member connected to said arms, 95 and means for operating said blades simultaneously.

3. A switch construction including two separately hinged blades, contact jaws and terminals appurtenant to each of said blades, 100 a pair of links pivotally connected together at one end and each link being pivotally connected at the other end to one of said blades, guided means for the connected ends of said links and means for operating one of said 105 blades.

4. A switch construction including two oppositely disposed blades, a hinge jaw for each of said blades, an electrical connection between said hinge jaws, an appurtenant contact jaw and terminal for each blade, two insulating links pivotally connected together at one end and each link pivotally connected at its other end to one of the respective blades, the said links co-operating with said blades 115 to cause simultaneous movement of both blades when one blade is moved.

5. A switch construction including an insulating base, two oppositely disposed blades mounted on said base, each blade having a co-operating hinge post, a contact jaw and a terminal, two insulating links pivotally connected together at one end and each link being pivotally connected at its other end to one of the respective blades, a fuse receptacle having appurtenant terminals interposed between the hinge jaws of said blades and electrically connected with said hinge jaws and an operating member connected to one of said blades. 120 125 130

6. A switch construction including two single pole switch units, each unit comprising a hinge post, a blade pivoted to said post and a stationary contact for said blade, 5 two link members pivotally connected together at one end, and each link member pivotally connected at its other end with one of the respective blades, said switch units being spaced in overlapped parallel relation 10 and said link members being positioned between said hinge posts, whereby the movement of one of said blades causes a simultaneous movement of the other blade.
7. A switch construction comprising an insulating base, switch jaws having circuit terminals connected to opposite edges of said base, a hinge post supported by said base adjacent each of said switch jaws, a blade hinged to each post and having an end adapted 15 to coact with the switch jaw at the opposite edge of said base, and a folding link connecting said blades.
8. A switch construction comprising an insulating base, switch jaws having circuit terminals connected to opposite edges of said base, a hinge post supported by said base adjacent each of said switch jaws, a blade hinged to each post and having an end adapted to 20 coact with the switch jaw at the opposite edge of said base, a folding link connecting said blades, an insulating fuse receptacle, fuse terminals mounted therein and supporting and conducting posts connected to said hinge posts and to said fuse terminals, respectively, and supporting said insulating 25 fuse receptacle.
9. A switch construction including an insulating base having a guiding recess, a pair of switch blades mounted on said base, appurtenant contacts and terminals for said blades, a hinged link connecting said blades and guided in said guiding recess, fuse terminals connected respectively to said blades and an operating member connected to one 30 of said blades.
10. A switch construction including an insulating base having a guiding recess, two switch blades mounted on said base at opposite sides of said recess, appurtenant contacts and terminals for said blades, a folding link 50 mechanically connecting said blades and guided in said guiding recess, and an operating member connected to one of said blades.
11. An electric switch including an insulating base, two hinge posts mounted on said base, two switch blades hinged respectively to said posts, appurtenant contacts and terminals for said blades, a folding link connecting said blades, an insulating fuse carrying member supported by said hinge posts 55 and having oppositely disposed fuse terminals electrically connected respectively to said blades at all times, and means for operating said blades simultaneously.
12. An electric switch including an insulating base, two hinge posts mounted on said base, a switch blade hinged to each of said posts, appurtenant contacts and terminals for said blades, an extension bracket secured to each hinge post, an insulating fuse carrying 60 member supported by said brackets, oppositely disposed fuse terminals mounted on said member and connected respectively to said brackets, and means for operating said blades simultaneously.
13. A switch construction including an insulating base, two single pole switch units mounted on said base, each unit comprising a hinge post, a switch blade pivoted to said post and a stationary contact for said blade, 75 two link members pivotally connected together at one end and each link member pivotally connected at its other end to one of the respective switch blades, two oppositely disposed fuse terminals, each fuse terminal being electrically connected at all times to one of the respective hinge posts and means for simultaneously operating said blades.

BENJAMIN E. GETCHELL.
